ALONZO E. RHOADES, OF HOPEDALE, MASSACHUSETTS, ASSIGNOR TO DRAPER CORPORATION, OF HOPEDALE, MASSACHUSETTS, A CORPORATION OF MAINE.

THREAD PARTER AND CLAMP.

Application filed January 15, 1925. Serial No. 2,573.

To all whom it may concern:

Be it known that I, ALONZO E. RHOADES, a citizen of the United States, residing at Hopedale, in the county of Worcester and State of Massachusetts, have invented an Improvement in Thread Parters and Clamps, of which the following description, in connection with the accompanying drawings, is a specification, like characters on the drawings representing like parts.

This invention relates to thread parters and clamps for use in filling replenishing looms.

It is now the general practice to provide filling replenishing looms with a shuttle feeler having associated therewith a thread parter and clamp for parting the filling between the shuttle and cloth selvage when filling replenishment is effected and positioning the end of the filling leading to the cloth selvage for the action of the temple thread cutter. The shuttle feeler thread cutter or parter is now ordinarily formed of a fixed and a movable member, the latter of which is actuated by the lay when the shuttle feeler is in its rearward shuttle feeling position, and mounted on the shuttle feeler at the side of the thread parter there is usually a thread clamp between which and the movable thread cutter or parter the thread end leading to the cloth selvage is to be clamped and held, so that when the shuttle feeler returns to its forward position the end leading to the cloth selvage will be presented to the temple thread cutter.

As heretofore ordinarily constructed, the thread clamp and movable member of the thread parter have been arranged face to face, that is, the side of the thread parter bore against the side of the thread clamp, with the result that when the parter was actuated to part the thread, the end of the filling leading to the cloth selvage would fail to be clamped between the parter and clamping member, or the movement of these members past each other during the clamping operation would cause breakage of the thread at the clamp and consequently the end of the filling leading to the cloth selvage would not be positioned for the action of the temple thread cutter.

One of the objects of the present invention is to provide a thread parter and clamp wherein a space is provided between the side faces of the parter and clamp to re-

ceive the end of the filling and thereafter clamp the filling end by movement of the parter and clamp relatively in a lateral direction to pinch the thread between them.

In accordance with the present invention, the clamping member underlies the thread leading from the shuttle to the cloth selvage when the shuttle feeler is in its rearward shuttle feeling position, and upon actuation of the parter to part the thread the clamp itself is moved in an opposite direction to lift the filling end that it may be clamped between the parter and clamping member before the filling is cut or parted.

The invention and novel features of the structure will best be made clear from the following description and the accompanying drawings showing one good form thereof.

In the drawings:

Fig. 1 is a perspective view of a shuttle feeler having the present invention associated therewith, some of the parts being broken away;

Fig. 2 is a side elevation of the shuttle feeler thread parter and clamp, showing the relation of parts when the movable member of the parter is actuated to part the thread;

Fig. 3 is an end view of the parts shown in Fig. 2, looking in the direction of the arrow, Fig. 2, and showing the thread as having been entered into the space between the parter and clamp prior to the cutting operation;

Fig. 4 is an enlarged detail view, showing the thread end leading to the cloth selvage as having been parted after having previously been clamped; and

Fig. 5 is a section on the line 5—5 of Fig. 1.

The shuttle feeler may be of any usual character and mounted for movement into its rearward shuttle feeling position on call for replenishment of filling. As shown, the loom frame has secured thereto a bracket 1 which may be adjustably mounted on the loom frame by a bolt 2 entering a slot 3 formed in the bracket member. The shuttle feeler 4 is shown as mounted for rocking movement on a stud 5 extending from the bracket 1 as usual in this type of shuttle feeler, and extending from the bracket 1 is a guide 6 for directing the movement of the shuttle feeler as it is turned to and from its shuttle feeling position.

Extending from the shuttle feeler 4 is a pin 7 which is engaged between the two arms 8 and 9 for moving the shuttle feeler to and from its rearward position, as usual in this type of mechanism. The arms 8 and 9 are connected to the transverse or rock shaft (not shown), but since such details form no essential part of the present invention and are now well understood in the art, they are not hereinafter described.

The shuttle feeler 4 has its end portion 10 extending rearwardly and is provided with the usual opening 11 for engagement with the shuttle, provided the latter is not properly boxed, and secured to the inner face of the end portion 10 of the shuttle feeler is the fixed thread parter 12, which may be conveniently formed as a blade secured as usual to the shuttle feeler. The cutting edge portion 13 of the fixed blade 12 is shown as slightly below the surface 14 of the shuttle feeler, on which the filling end *a* is supported when the shuttle feeler is in its rearward feeling position.

Pivottally mounted on the pin 15 extending laterally from the end 10 of the shuttle feeler is the movable thread parter 16, the frontwardly extending end portion of which is provided with an actuating member or toe 17 which is adapted to be struck by the lay or a part carried thereby, to actuate the movable member of the parter to part the thread *a* between the shuttle 18 and cloth selvage.

At the side of the movable thread parter 16 is the thread clamp or clamping member 19 having an enlarged opening 20 through which the pin 15 extends, and provided with a bifurcated end portion 21 for engagement with a pin 22 extending laterally from the end portion 10 of the thread parter. The pin 22 passes through an enlarged opening 23 formed in the thread parter, so that the latter may be free to partake of its thread parting movement. From the construction thus far described it will be apparent that the movable member of the thread parter is pivotally supported on the shuttle feeler for movement to and from its thread parting position, and at the side of the thread parter is the thread clamp 19 which is itself pivotally mounted upon the pin 22 located frontwardly of the pin 15 and extending laterally from the shuttle feeler.

The thread parter 16 has a rearwardly extending end portion 24 which underlies the thread *a* when the shuttle feeler with the thread parter and clamp are moved to rearward functioning position.

The clamping member 19 is provided with a slot 25 into which extends a pin 26 projecting from the movable thread parter 16, the construction being such that when the thread parter 16 is actuated, as hereinbe-

fore described, it will impart to the thread clamp 19 movement in an opposite direction, to thereby lift the filling thread *a* as the thread parter is actuated.

In accordance with the present invention, the thread parter and clamp have a relative lateral movement to first provide a space between them to receive the thread to be parted, and thereafter to clamp or pinch the thread between the adjacent faces of the thread parter and thread clamp.

As shown in the present instance of the invention, the pin or bolt 15 has mounted thereon a head 27 between which and the outer surface of the thread clamp 19 is interposed a spring 28 normally tending to press the clamp 19 towards the parter 16, and means are provided in accordance with the present invention to restrain such relative movement of the parter and clamp until the thread to be parted and clamped has been placed in a space between the parter 16 and the clamp 19.

In the present instance of the invention, as indicated in Fig. 5, the clamp 19 is provided with a spacer 29 which normally bears upon the face of the parter 16 and maintains the parter 16 and clamp 19 in separated relation to provide a space 30 between them for the reception of the thread to be parted and clamped, and to permit the parter and clamp to be moved relatively in a lateral direction to clamp the thread when once it has been placed in a space between the two and preferably before the thread is parted, the movable member 16 of the parter is provided with a recess 31 which, as the parter 16 is actuated to part the thread, comes opposite the spacer 29 and permits the parter and clamp to move laterally into thread pinching position, as indicated in Fig. 4. The spacer 29 is shown as formed by a headed bolt or rivet passed through the clamp 19, as a convenient means of forming the spacer to hold the clamp and parter in separated relation during the preliminary entering of the thread between the two, and the recess 31 is shown as formed by a depression in the adjacent side face of the parter 16, the construction being such that when the shuttle feeler is in its rearward feeling position and the filling to be parted is resting in the recess 11 of the shuttle feeler and on top of the underlying portion 24 of the clamp and the parter is actuated, the thread will be lifted by the clamp 19 and pass freely into the open space 30 between the parter and clamp as the parter performs its parting function, whereupon, or preferably just prior to the parting of the thread, the recess 31 of the parter will pass in front of the spacer 29 and permit relative lateral movement of the parter and clamp to pinch or bite the thread already positioned between them.

After the thread has thus been

clamped between the parter and clamping member and is securely held, the parter 16 will part the thread by coaction with the fixed parter member 12, as indicated in 5 Fig. 4.

By preliminarily entering the filling to be parted in the space between the parter and clamp and then causing relative lateral movement of the parter and clamp to pinch 10 and hold the thread, all liability of the thread being broken between the parter and clamp is avoided and the filling end leading 15 to the cloth selvage will unerringly be moved into position for the action of the temple thread cutter.

Preferably the thread will be clamped, as described, before it is parted, but these two operations may take place simultaneously if desired.

20 As indicated in Figs. 2 and 3, it will be noted that the filling thread is first located in the space between the parter and clamp, as the former moves in the performance of its cutting function, and that thereafter the 25 relative lateral movement of the parter and clamp will hold or pinch the filling already placed between them before the thread itself is parted.

The lay 32 may if desired be provided 30 with an opening 33 for the entrance of the end of the shuttle feeler parter and clamp when these members are moved to their rearward functioning position.

Extending from the front portion of the 35 movable member 16 of the parter is a pin 34 which serves in connection with a swinging trip member 35 to open the parter as the shuttle feeler moves towards rearward position, and after the parter has been closed 40 and the thread has been clamped, as described, such pin 34 will pass the trip 35 by swinging the latter as the shuttle feeler moves to its front position.

As indicated, in the present form of the 45 invention the trip 35 is pivotally mounted at 36 on an arm 37 which may be conveniently secured to the bracket 1, as usual in this type of mechanism. The trip 35 has a lateral projection 38 adapted to engage a 50 stop 39 on the arm 37 to limit its rearward swinging movement but permit frontward swinging movement of the trip.

What is claimed is:

1. In a loom, the combination of a shuttle 55 feeler, a thread parter having a movable member mounted on the shuttle feeler, a thread clamp, laterally separated from the parter to provide a space for the reception of the thread to be parted when the feeler 60 is in rearward position, means normally acting to cause relative lateral movement of the clamp and parter to pinch the thread between them and restrained from effecting such relative lateral movement until the 65 thread has been received in the space be-

tween the parter and clamp as the parter is actuated to part the thread.

2. In a loom, the combination of a shuttle feeler, a thread parter and clamp mounted thereon, means for holding the parter 70 and clamp laterally separated to receive the thread between them, and means for causing relative lateral movement of the parter and clamp to pinch the thread between them before it is parted. 75

3. In a loom, the combination of a shuttle feeler, a thread parter and clamp thereon, yielding means normally acting to force them laterally together, and means for maintaining them laterally separated until 80 the thread is caught between them during operation of the parter.

4. In a loom, the combination of a shuttle feeler, a thread parter and clamp thereon, means normally acting to force the parter 85 and clamp laterally face to face to pinch the thread between them, and means for holding them laterally separated for the reception of the thread until the parter and clamp are moved into a predetermined relation during the operation of the parter. 90

5. In a loom, the combination of a shuttle feeler, a movable thread parter mounted on the shuttle feeler, a thread clamp, and means acting laterally for holding the parter and clamp separated to provide a space for the reception of the thread between them until the parter is actuated to part the 95 thread and then permitting relative lateral movement of the parter and clamp to pinch 100 the thread between them.

6. In a loom, the combination of a shuttle feeler, a thread parter and a thread clamp mounted on the shuttle feeler, connections 105 between them for causing closing and opening movement of the parter to effect like movement to the clamp, means for causing lateral separation of the parter and clamp when in open position to provide a space for the thread, and means for relatively moving the parter and clamp laterally towards each other to clamp the thread before it is parted. 110

7. In a shuttle feeler thread cutter and clamp, the combination of a movable cutting blade, a clamping member mounted alongside of the cutting blade, a spring normally acting to force the cutting blade and clamping member with their side faces together, and means between the blade and clamping member to hold them laterally separated until a predetermined position is reached by the blade during the cutting operation. 115

8. A shuttle feeler, a thread parter pivotally mounted thereon, a thread clamp at the side of the parter, a spring normally forcing the parter and clamp together side by side, and means between them acting to hold them in separated relation laterally until 120 125 130

4
a predetermined period in the operation of parting the thread.

9. A shuttle feeler thread parter and clamp, comprising a movable thread parter having a recess, a thread clamp having a spacer to bear upon the face of the parter to maintain them in separated relation un-

til the parter is actuated to part the thread and then entering the recess in the parter to permit the parter and clamp to clamp 10 the thread between them.

In testimony whereof I have signed my name to this specification.

ALONZO E. RHOADES.
